UNITED STATES PATENT OFFICE.

CHRISTIAN D. WISELOGEL, OF ALBION, MICHIGAN, ASSIGNOR TO THE GALE MANUFACTURING COMPANY, OF SAME PLACE.

CULTIVATOR OR HARROW TOOTH.

SPECIFICATION forming part of Letters Patent No. 462,675, dated November 3, 1891.

Application filed July 11, 1891. Serial No. 399,137. (No model.)

To all whom it may concern:

Be it known that I, CHRISTIAN D. WISELOGEL, a citizen of the United States, residing at Albion, in the county of Calhoun and 5 State of Michigan, have invented a new and useful Improvement in Teeth for Harrows, Cultivators, &c., of which the following is a specification.

My invention relates to cultivators; and its 10 purpose is to provide an improved form for the shank for supporting the tooth and improved methods of engaging the tooth with the shank, and an improved form for the tooth, whereby it is adapted to the improved form 15 of engagement with the shank.

My invention relates specifically to that form of tooth and method of engaging the tooth where the bolt holding a tooth to the shank has its support back of the tooth to 20 avoid exposing it to the wear of the tooth, and where the tooth may be removed from the shank without removing the bolt and breaking or disturbing the polished surface of the tooth; also, in further provision for 25 avoiding a shearing strain on the bolt holding the tooth.

In the drawings, Figure 1 shows the shank, plate for holding the tooth, &c. Fig. 2 shows the parts assembled.

30 In the drawings, A is the shank, which is formed, as shown, by taking a flat bar of iron and forging the section between the upper point of support and the point of engagement with the tooth, so as to bring the greatest 35 weight of cross-section in the direction of the strain incident to the work. The lower section of the shank is provided with the opening a, rectangular in form. B is an independent plate, formed as shown and provided

40 on the back with the lug or projection E, adapted to fill the orifice a in the shank, but not of sufficient depth to extend entirely through the orifice. Extending through the 45 plate B and through the lug or projection E is the plate F, having its head countersunk in the face of the plate B. To the face of the plate B is riveted by rivets D the tooth B'. This engagement between the tooth B' and the plate B is permanent, and the polishing 50 of the wearing-face of the tooth B' is over

the head of the rivets D and adapted to leave a perfectly smooth surface on the face of the tooth. When the tooth and plate are thus engaged, the bolt F is also permanently engaged with them, and these parts so assembled are engaged with the shank by inserting the projection E in the rectangular opening a in the shank, and the washer f' is passed over the bolt and the nut f screwed on and the whole tightened to place. The washer f' 60 is of sufficient size to cover the opening a.

The projection E, as I have stated, is not of sufficient depth to extend entirely through the orifice a, so that the tightening of the nut f does not bring the face of this projection against the washer f', but rather seats the projection E firmly in the orifice a and brings the plate B firmly against the front of the shank. It is manifest that this construction brings the shearing strain of the tooth 70 and its supporting parts on the projection E rather than on the bolt F, leaving the bolt F merely holding the tooth in its place on the shank. The rectangular form of the projection serves further to avoid twisting of the 75 tooth sidewise. This feature is materially aided by the construction of the shank A, in which the forged portion a² is extended forward around the point a', so as to fit the plate B and to bring the tooth B' at its upper portion back against the shank and avoid a space 80 for the accumulation of débris between the shank and the tooth.

It is manifest that the tooth and its attachment may be removed and reversed and still 85 retain the full value of my special method of engaging it with the shank and utilize the special form of the shank shown.

What I claim is--

1. The combination of a shank A, having 90 angular perforation a extending clear through the same, a cultivator-tooth point provided with a block or casting engaged therewith and having an angular projection E, adapted to fit within and project partly through said 95 perforation, a bolt F, extending through said projection, and a nut f and washer f', extending beyond the edges of said perforation, whereby the block is bound to the shank and the angular projection E firmly seated within 100

the orifice a and the bolt relieved from lateral strain, substantially as described.

2. The combination of a shank A, provided with recessed portion a' , and having an angular perforation a , extending through the extremity of the shank, cultivator-tooth B, block C, adapted to fit in the recess a' and provided with an angular projection extending partly through the angular perforation a ,

and the bolt, washer, and nut, substantially as shown and described.

In testimony whereof I sign this specification in the presence of two witnesses.

CHRISTIAN D. WISELOGEL.
